UNITED STATES PATENT OFFICE

WILLIAM A. BATTEY, OF HAVERFORD, AND CHARLES A. JAMISON, OF PHILADELPHIA, PENNSYLVANIA, ASSIGNEES TO PENNSYLVANIA CRUSHER COMPANY, OF NEW YORK, N. Y., A CORPORATION OF NEW YORK

CRUSHER

Application filed October 18, 1927. Serial No. 226,841.

Our invention relates more particularly to single roll crushers intended for heavy duty and designed to operate upon large masses of rock, coal, and the like, and where the shock attending the crushing roll when striking these masses and crowding them against the anvil formed by the breaker-plate must be resisted by the side frames of the machine.

10 In general, our structure follows the lines of single roll crushers of the usual type, but the feature of our invention is the provision of side frames preferably of all-steel construction; such side frames being in the form 15 of integral castings or fabricated structures of large size, spaced apart laterally and connected together by heavy tie members which may be bolted or otherwise secured to said side frame to form the complete crusher structure.

In our improved structure, the side frames in side elevation are substantially U-shape in contour; being recessed intermediate their ends for the reception of bearings carrying 25 the shaft of the crushing roll, and when such bearings are in place and the shaft is in its proper relative position, a space is left in each side frame above the upper bearing cap. The usual practice, heretofore, has been to 30 tie together the two portions of the side frames which flank this space or recess by large bolts extending substantially the full length of said side frames.

In practice great care had to be exercised 35 in drawing up these bolts to their final positions respectively, in order to avoid setting up strains in the lower portion of the side frames which might cause the latter to give away under stress of heavy duty, and the 40 main object of our invention is to provide an improved construction whereby the space or recess in each side frame above the upper bearing cap may be closed and the end portions of the side frames flanking such open 45 space properly connected together in a manner that will insure a stable and rigid structure and avoid the setting up of any strains in any portion of said side frames.

A further object of our invention is to provide a filling piece for the space or recess of

each side frame, which filling piece may be a casting of heavy construction with reinforcing ribs and of such size and shape as to properly fit between the walls of such space; said walls, as well as the engaging ends of 55 the filling piece which meet the same being, by preference, properly faced to insure the desired fit. After such filling pieces are disposed in their proper position, they are held in place by bolts which pass through the body 60 of the same and through heavy bosses formed on the side frames adjacent the walls of each space; said bolts being threaded at each end for the reception of nuts which may be drawn up independently and insure a rigid 65 connection of the parts without setting up strains.

These and other features of our invention are more fully described hereinafter; reference being had to the accompanying drawings, in which:

Figure 1, is a longitudinal sectional elevation of one form of single roll crusher to which our invention may be applied; the side frame only being shown by full lines, 75 while the connecting or tie members and crushing mechanism are shown by broken lines.

Fig. 2, is a side elevation of a side frame for single roll crushers constructed in accordance with our invention.

Fig. 3, is a plan view of the side frame, partly in section on the line III—III, Fig. 2.

Fig. 4, is an end view of the filling piece employed with the side frames, and

Fig. 5, is a vertical sectional view of the filling piece, taken on the line V—V, Fig. 2.

Fig. 2 shows in elevation a complete side frame illustrating our improved construction; being indicated generally at 1. In the 90 form disclosed in the drawings, such side frames may comprise an integral casting of steel, with top, bottom, and end flanges externally disposed, and indicated at 2, 3, 4 and 4^a, respectively. Longitudinal strengthening ribs or flanges 5, and vertical strengthening ribs or flanges 6, are preferably formed on its outer face, and such side frame is shaped to provide, intermediate its end flanges 4 and 4^a, a recess 10; the portions of 95 100

said side frame between said recess and said end flanges being indicated at 1^a and 1^b, respectively. The lower portion of the recess is curved, as indicated at 10^a, and an extension 11, integral with the side frame receives the usual bushing 11^a providing the lower bearing for the shaft 12, of the crushing roll 13. A bearing cap 14, of any usual type is provided for the shaft and its bushing, and above this bearing cap, the recess 10 provides an open space between the portions 1^a and 1^b, of such side frame, which space receives a filling block, indicated at 15, and forming the subject of our invention.

15 The oppositely disposed walls 10^b of this space are properly faced and shouldered at 10^c for the reception of this filler number 15, shown more particularly in Figs. 3, 4 and 5; a portion of said filling member fitting between said walls 10^b and closing the upper portion of the space 10 between the end portions 1^a and 1^b of the side frame. In order that the filling members of the respective side frames may be properly secured in place 20 and perform the desired function, we provide bolts 16, which pass through the same and through heavy ears or bosses 17 and 18, formed on the outer surface of the end portions 1^a and 1^b of said side frames adjacent the walls 10^b of the space 10; such bolts being held in place by nuts 19, one on each end of each of said bolts. These nuts may be longitudinally grooved so as to be taken up by a spanner wrench of the hook type.

30 The filler members 15 may be and preferably are in the form of hollow steel castings, which are open on the under side, and more particularly illustrated in Figs. 3, 4 and 5. They are preferably of the shape shown, having side walls 20 and 20^a, the former flush with the outer surface of the flanges 2; end walls 21; an internal reinforcing rib 22 parallel to the side walls, and a cross rib 22^a. The end walls of the filler member rest on the shoulders 10^c and engage the walls 10^b of the space 10; filling the upper portion of the space between the end portion 1^a and 1^b of the side frames above the bearing, so that the nuts 19 on the securing bolts 16 may be set 40 up very tightly without producing any strain or tension in any portion of said side frames. The wall 20^a of the filling member depends below the wall 20 and is provided with end projections or flanges 22^b, vertically disposed, and arranged to engage the inner wall of the side frames; the surface 22^c of said end flanges engaging the inner surfaces of the walls of the end portions 1^a and 1^b, adjacent to the walls 10^b flanking said space 10. The 50 filling block 15 and bolt 16 constitute a combined compression and tension member for each side frame which prevents the setting up of strains practically unavoidable with the ordinary structures bolted in the manner 55 above referred to.

In the final condition of use, each side frame of a single roll crusher built in accordance with our invention, is a substantially single, unitary, structure without any tendency to produce the stresses and strains common to the side frames employed with the usual type of single roll crushers. At the same time the filler members which we provide may be readily removed to gain access to the crushing roll or the bearings, and when 70 the bearing caps 14 of the latter are removed, the shaft, together with the crusher roll, may be readily lifted out.

75 By preference, the filler members carry detachable wear plates 23 secured to their inner face, (indicated by broken lines, Figs. 1 and 5,) which plates overhang the ends of the crusher roll so that any small particles accompanying the larger size rock or other material being crushed will be diverted from the 80 bearings, and directed into the crushing zone. Dust guards 24 are preferably disposed externally of and beneath the filler blocks and above the upper bearing cap, and may be carried by the depending wall 20^a of the filler blocks; recesses 25, for the reception of holding 85 screws 26, being shown in Fig. 2.

90 The greatest shock to the side frames occurs when huge rock masses are caught between the crushing roll and the anvil, and it is at 95 this time that the maximum strength of the side frame is called into use. The necessity of removing the crushing roll and shaft unit under modern practice makes the provision of a recess intermediate the ends of the said 100 side frames unavoidable, and the filling members fitting within the recesses between said end portions and properly secured thereto provide a rigid structure and a substantially 105 unitary frame, well able to resist the stress 110 to which crushers of this character are subjected without danger of breakage.

We claim:

1. The combination, in crushing machinery employing crusher rolls, of side frames in the form of integral castings of massive construction; said side frames being substantially U-shape in contour with end portions flanking a recess provided for the insertion and removal of the crusher roll shaft, filling 110 members fitting between the walls of said recess and closing the space between said end portions longitudinally of said side frames, and means connected to said side frames for holding said filling members in rigid relationship wth respect thereto.

115 2. The combination, in crushing machinery employing massive crusher rolls, of side frames in the form of integral castings of massive construction each of which provides a lower bearing for the crusher roll shaft; said side frame being substantially U-shape in contour with end portions flanking a recess above the lower bearing and the opposite 120 walls of said recess being substantially in per-

- pendicular alignment, filling members fitting between said walls and closing the space between said end portions longitudinally of said side frames, and means connected to said side frames longitudinally thereof for holding said filling members in rigid relationship with respect thereto.
3. The combination, in crushers employing massive crusher rolls, of side frames in the form of integral castings of massive construction; said side frames being substantially U-shape in general contour with end portions flanking an intermediate recess provided for the insertion and removal of the crusher roll shaft, filling members fitting between the walls of said recess and closing the space between said end portions longitudinally of said side frames, and bolts passing horizontally through said filling members and through bosses on the side frames for holding said filling members in rigid relationship with respect to said side frames.
4. The combination, in crushers employing massive crusher rolls, of side frames in the form of integral castings of massive construction each of which provides a lower bearing for the crusher roll shaft integral therewith; said side frames being substantially U-shape in contour with end portions flanking a recess above the lower bearing and the opposite walls of said recess being substantially in perpendicular alignment, filling members closing the space between the walls of said end portions longitudinally of said side frames, and bolts passing horizontally through said filling members and through bosses on the side frames for holding said filling members in rigid relationship with respect to said side frames.
5. The combination, in crushers, of side frames in the form of integral castings of massive construction; said side frames being substantially U-shape in contour with end portions flanking an intermediate recess, filling members fitting between said walls above the bearing and filling the space between said end portions longitudinally of said side frames, and means connected to said side frames longitudinally thereof for holding said filling members in rigid relationship with respect thereto; the ends of said filling members resting on shoulders formed on said walls and having end flanges engaging the inner surface of the side frames directly adjacent the walls of the recess receiving the filling member.
6. The combination, in crushers employing massive crusher rolls, of side frames in the form of integral castings of massive construction each of which provides a lower bearing for the crusher roll shaft; said side frames being substantially U-shape in contour with end portions flanking a recess above the lower bearing having substantially shouldered sides, filling members fitting between said walls above the bearing and filling the space between said end portions longitudinally of said side frames, and means connected to said side frames longitudinally thereof for holding said filling members in rigid relationship with respect thereto; the ends of said filling members resting on shoulders formed in said walls and having end flanges engaging the inner surface of the side frames directly adjacent the walls of the recess receiving the filling member.
7. A side frame construction for crushers, comprising an integral casting substantially U-shape in contour by reason of a recess intermediate end portions of the same; said recess having shouldered side walls, a filling member engaging said side walls and shoulders and closing the upper portion of said recess longitudinally of said side frame, and means connected to said side frames longitudinally thereof for securing said side frames and filling members in rigid relationship.
8. A side frame construction for crushers, comprising an integral casting substantially U-shape in contour by reason of a recess intermediate the end portions of the same; said side frames consisting of a web with reinforcing ribs and flanges and said recess having shouldered side walls, a filling member engaging said side walls and shoulders and closing said recess longitudinally of said side frame said filling member lying flush with the upper surface of the side frame, and means for securing said side frames and filling members in rigid relationship.
9. A side frame construction for crushers, comprising an integral casting substantially U-shape in contour by reason of a recess in the upper portion of the same intermediate end portions thereof; said side frame consisting of a web with reinforcing ribs and flanges and said recess having shouldered side walls, a filling member engaging said side walls and shoulders and closing said recess longitudinally of said side frame, bolts passing through said filling members and through bosses on the side frames for holding said filling member in rigid relationship with respect to said frame, and nuts for securing said bolts in place.
